UNITED STATES PATENT OFFICE

WILLIAM E. WHITE, OF CHICAGO, ILLINOIS, ASSIGNOR TO KALMAN STEEL COMPANY,
OF CHICAGO, ILLINOIS, A CORPORATION OF DELAWARE

BUILDING CONSTRUCTION

Application filed April 23, 1928. Serial No. 272,133.

My invention relates to building construction, and particularly to novel means for holding metal lath and sleepers to the tops of beams or girders.

5 It is common practice to suitably mount the floor girders and to place thereon a layer of metal lath, then to position floor sleepers on the beams, extending either parallel to or transversely of the beams, and suitable means 10 should be provided for securing the sleepers to the beams through the lath. Inasmuch as the flange width of the beams varies in different installations and, in fact, in the same building at different parts thereof, the fastening 15 device should adapt itself to such variations and to variations in the position of the sleeper.

In order to accomplish this result, I have 20 provided a sleeper chair and a novel fastening clip composed of two sections of wire adapted to interlock, and each wire having a downwardly projecting portion terminating in a hook adapted to underlie the beam flanges.

25 The invention will be more readily understood by reference to the accompanying drawings, in which,—

Fig. 1 is a sectional view through a sleeper and beam with my novel clip applied thereto;

30 Fig. 2 is a side elevation thereof;

Fig. 3 is a plan view;

Fig. 4 is an enlarged, perspective view of the chair;

35 Fig. 5 is an elevation, somewhat enlarged, of the combined clip elements;

Fig. 6 is an end view of one of the clips; and

Fig. 7 is a plan view of the construction shown in Fig. 5.

40 In the drawings, an expanded metal beam is shown comprising shear elements 10 and flanges 11. Metal lath 12 is intended to be laid on top of the beam, and on the lath is superposed a wood sleeper 13. The sleeper 45 may extend parallel to the beam, as shown, or transversely thereto, as occasion may require.

As a means for securing the sleeper in place, I provide the chair shown in Fig. 4, consisting of a floor or base plate 14 having bulges 50 or ribs 15 struck up therefrom near its side

edges, together with vertically extending ears or lugs 16 on opposite sides, apertured as at 17 to receive nails.

The fastening clip of my invention comprises a pair of wire elements of duplicate 55 construction, each consisting of a straight portion 18, a laterally bent portion 19, a downwardly projecting portion 20, and a hook 21. The laterally bent portion 19 is so proportioned that the straight portion of a co-operating clip element may be received 60 therein, as best shown in Fig. 7. When the parts are combined, as shown in Figs. 5 and 7, the two downturned ends may be projected 65 through the interstices in the lath with the hook portions spread apart sufficiently to clear the flanges of the beam. By pulling on the free ends 22 of the straight portions, the hooks are drawn toward each other into close 70 engagement with the beam flanges, and thereafter the free ends are bent around the portions 19 and may occupy a space beside the sleeper. This clip serves as a convenient 75 means for securing lath to a beam whether or not a chair is to be used. If the chair is to be installed, as shown in the drawings, it is placed immediately on the lath and the straight portions 18 of the clip occupy the space beneath the sleeper and between the 80 ribs or bulges 15. The ribs 15 serve to elevate the sleeper sufficiently above the beam so that the concrete may flow under the sleepers in order to suitably support the same.

The sleeper may be positioned in either of two right-angularly disposed positions without interference in any way with the operation of the clip.

Obviously, the clip adapts itself to all forms and dimensions of beams, and, when firmly secured by manual operation, is permanently held in place.

Modifications and variations may be made in the construction without departure from the spirit of my invention.

I claim:

1. In combination with a flanged beam and lath resting thereon, of a clip consisting of two separate lengths of wire of substantially 95 duplicate construction, each having a straight portion and a bent end terminating in a hook, 100

said straight portions being adapted to lie in side by side relation with the straight portion of one section underlying the bent end portion of the other section, said bent end portions being adapted to be projected through the lath, the hooks being adapted to engage with the flanges of the beam, and the free ends of the wire sections to be bent at an angle to confine the clip in holding relation.

10. 2. The combination with a flanged beam and lath resting thereon, of a sleeper chair having wings and a seat adapted to rest on said lath above the beam, and a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent end portions being adapted to be projected through the lath with the straight portions above the seat of the chair, the hooks being adapted to engage with the flanges of the beam, and the free ends of the wire sections to be bent at an angle to confine the clip in holding relation.

3. The combination with a flanged beam and lath resting thereon, of a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent ends being disposed in a downward direction with the hook portions lying in a plane parallel with said straight portions, said bent end portions being adjusted to be projected through the lath, the hooks being adapted to engage with the flanges of the beam, and the free ends of the wire sections to be bent at an angle to confine the clip in holding relation.

4. The combination with a flanged beam and lath resting thereon, of a sleeper chair having wings and a seat adapted to rest on said lath above the beam, and a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent ends being disposed in a downward direction with the hook portions lying in a plane parallel with said straight portions and adapted to be projected through the lath, the hooks being adapted to engage with the flanges of the beam, and the free ends of the wire sections to be bent at an angle to confine the clip in holding relation.

5. The combination with a flanged beam and lath resting thereon, of a sleeper chair having wings and a seat, adapted to rest on said lath above the beam, projections on the base of said chair extending upwardly whereby to raise the sleeper from contact with the base, and a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent end portions being adapted to be projected through the lath with the straight portions above the seat of the chair, the hooks being adapted to engage with the flanges of the beam, and the free ends of the wire sections to be bent at an angle to confine the clip in holding relation.

6. The combination with a flanged beam and lath resting thereon, of a sleeper chair having wings and a seat adapted to rest on said lath above the beam, a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent end portions being adapted to be projected through the lath with the straight portions above the seat of the chair, the hooks being adapted to engage with the flanges of the beam and the free ends of the wire sections to be bent at an angle to confine the clip in holding relation, and means on said chair for receiving the sleeper in either parallel or transverse position relative to the beam.

7. The combination with a flanged beam and lath resting thereon, of a clip consisting of two separate lengths of wire of substantially duplicate construction, each having a straight portion and a bent end terminating in a hook, said straight portions being adapted to lie in side by side relation with the straight portion of one section underlying the bent end portion of the other section, said bent ends being disposed in a downward direction with the hook portions lying in a plane parallel with said straight portions, said bent end portions being adapted to be projected through the lath, the hooks being adapted to engage with the flanges of the beam and the free ends of the wire sections to be bent at an angle to confine the clip in holding relation, said chair being shaped to receive the sleeper in either a parallel or cross position relative to the beam.

8. The combination with a flanged beam and lath resting thereon, of a sleeper chair having wings and a seat adapted to rest on said lath above the beam, a clip consisting

of two separate lengths of wire of substantially duplicate construction, each having a straight portion and a bent end terminating in a hook, said straight portions of one section underlying the bent end portion of the other section, said bent ends being disposed in a downward direction with the hook portions lying in a plane parallel with said straight portions, said bent end portions being
5 adapted to be projected through the lath, the hooks being adapted to engage with the flanges of the beam, and the free ends of the wire sections to be bent at an angle to confine the clip in holding relation, said chair being
10 shaped to receive the sleeper in either a parallel or cross position relative to the beam.

9. The combination with a flanged beam and lath resting thereon, of a sleeper chair having wings and a seat adapted to rest on
20 said lath above the beam, and projections on the base of said chair extending upwardly whereby to raise the sleeper from contact with the base and a clip consisting of two
25 separate lengths of wire of substantially duplicate construction, each having a straight portion and a bent end terminating in a hook, said straight portions being adapted to lie in side by side relation with the straight portion on one section underlying the bent end portion
30 of the other section, said bent end portions being adapted to be projected through the lath with the straight portions above the seat of the chair, the hooks being adapted to engage with the flanges of the beam and the
35 free ends of the wire sections to be bent at an angle to confine the clip in holding relation, said chair being adapted to be mounted to receive the sleeper in either a parallel or cross position relative to the beam.

40 In testimony whereof I have affixed my signature.

WILLIAM E. WHITE.
